AMINES AND PROCESS FOR THE PREPARATION
OF AMINES

Emil Schlittler, Basel, and Andreia Uffer, Riehen, Switzerland, assignors to Ciba Pharmaceutical Products, Inc., Summit, N. J.

Claims priority, application Switzerland May 21, 1948

10 Claims. (Cl. 260—296)

The present invention relates to a new process for the preparation of amines from amides with the same number of carbon atoms.

It is old to convert an acid amide, for instance, by the Hofmann degradation, into an amine which contains one carbon atom less than the starting amide. Various methods have also been described in the literature, according to which amides can be reduced to amines having the same number of carbon atoms. Such a reduction can be carried out catalytically with the aid of a copper-chromium oxide catalyst at a temperature of about 250° C. and at 200 to 300 atmosphere pressure [see "Neuere Methoden der präparativen organischen Chemie," page 132 (Berlin 1943)]. Amides may also be reduced to amides electrolytically [Fr. Fichter, "Organische Elektrochemie," page 265 et seq. (1942)]. These known processes are, however, bound up with disadvantages, particularly since the energetic reaction conditions which they entail give rise to undesired side-reactions. In many cases, it is entirely impossible according to the known methods to reduce amides to the desired amines at all.

A primary object of the present invention is the embodiment of a process for the conversion of amides into amines having the same number of carbons, which process is free of the aforementioned deficiencies of the prior art processes. Briefly stated, this object is realized according to the present invention, in connection with the conversion of the carboxylic acid amides to amines, by reducing the starting amide with lithium-aluminum-hydride.

The process according to the invention is applicable to a wide variety of amides, so that the initial amide may be a substituted or unsubstituted amide of an aliphatic, alicyclic, aromatic, araliphatic or heterocyclic carboxylic acid. The amide moiety may be of the open chain type, i. e. of the type of $-\text{CONH}_2$, or, as in the case of the cyclic amides, may form part of a ring, as in the lactams, for example the 2-pyridones or the 2-quinolones (cyclohexanones), and as in the dicarboxylic acid imides, such as the phthalimides; or quinolinic acid imides. The acid moiety of the amide being reduced may be substituted, for example by free or etherified hydroxy groups or by further amide groups, so as to obtain polyamines.

It is preferred, according to the present invention, to effect the reduction in an indifferent, anhydrous organic solvent medium in which the lithium-aluminum-hydride being used is soluble, and in this connection the preferred solvent is ether, although many others such as tetrahydrofuran, butyl ether, dioxane and the like may also be employed. Particularly good results are obtained with amides which are readily soluble in the solvent or diluent medium employed.

The process according to the present invention makes it possible to prepare amines in simple manner, which cannot be obtained at all or only with difficulty according to known processes, as for example amines whose nitrogen atom is connected with three different organic radicals.

2

An important advantage of the present process is that it is carried out at a relatively low temperature so that side-reactions are thus avoided. In general, carbon-to-carbon multiple bonds which may be present are not reduced. However, it is possible with suitably selected reaction conditions, for example by the use of increased quantities of reducing agent, extended reaction time and elevated temperature to saturate double bonds in certain cases, particularly double bonds in $\alpha:\beta$ -position with respect to the amide group. The new process is especially suitable, for example, for the preparation of 2,3-bis-(aminomethyl)-pyridines, such as 2,3-bis-(dialkylaminomethyl)-pyridines.

The amines which can be prepared according to the present invention are manifestly suitable for a wide range of uses such as detergents, pharmaceuticals and intermediates for the production thereof.

The invention is hereinafter set forth in greater detail by means of the illustrative examples which follow, but which are not intended to be limitative of the scope of the invention. In the said Examples the parts are by weight unless otherwise indicated, and the relationship between parts by weight and parts by volume is the same as that between grams and cubic centimeters. The temperatures are in degrees Centigrade.

EXAMPLE 1

Triethylamine

9.5 parts of lithium-aluminum-hydride are dissolved in 360 parts by volume of absolute ether; and to the resultant solution there are added 23 parts of *N,N*-diethyl-acetamide, dissolved in 300 parts by volume of absolute ether, at such a rate that the solution continues to boil gently. Upon completion of the reduction, water is added to the reaction mixture, which is also acidified with sulfuric acid and then extracted with ether for the removal of the acid and neutral reaction products. It is then made strongly alkaline with 10 N-caustic soda solution and again extracted with ether. Triethylamine having a boiling point of 89° is obtained from the ether extract.

EXAMPLE 2

Ethyl-propylamine

44 parts by weight of propionic acid-ethylamide in 600 parts by volume of absolute ether are added to 19 parts of lithium-aluminum-hydride in 720 parts by volume of absolute ether. Upon completion of the reaction further manipulation is carried out according to Example 1, and there is obtained ethyl-propylamine having a boiling point of 78°. Its hydrochloride melts at 222–223°.

EXAMPLE 3

β-Ethylbutylamine

To 1.03 parts of lithium-aluminum-hydride dissolved in 80 parts of absolute ether there are added, within 1 to 2 hours, 2.45 parts of α -ethyl-crotonic acid-amide in 400 parts by volume of absolute ether and the solution then kept at a gentle boil for about 20 hours. The reaction mixture is then decomposed with water, and then acidified. It is first extracted with ether, then made strongly alkaline with caustic soda and then again extracted with ether. From the ethereal solution there is obtained β -ethyl-butylamine, which boils at 71–75° and forms a picrate which melts at 168–169°.

EXAMPLE 4

N-(3,4,5-trimethoxy-benzyl)-dimethylamine

Proceeding in a manner analogous to that described in Example 4, there is obtained from 12 parts of 3,4,5-trimethoxy-benzoic acid-dimethylamide, by reduction with 4.6 parts of lithium-aluminum-hydride, the *N*-(3,4,5-tri-

methoxy-benzyl)-dimethylamine having a boiling point at 10 mm. pressure of 154-155°. From this amine, there can be obtained the picrate having a melting point of 146-147°.

EXAMPLE 5

β-phenyl-ethylamine

4.5 parts of lithium-aluminum-hydride are dissolved in 500 parts by volume of absolute ether and 13.5 parts of phenylacetamide in an extraction shell are added thereto. The ethereal solution is heated until all the phenyl-acetamide is extracted. Then the process set forth in the preceding examples is followed and there is obtained *β-phenyl-ethylamine* which boils at 78-80° under a pressure of 12 mm., and the picrate of which melts at 167-168°.

EXAMPLE 6

Iso-indoline

Upon proceeding analogously to the method described in the preceding example, 9.0 parts of lithium-aluminum-hydride are dissolved in 600 parts by volume of absolute ether and 14.7 parts of phthalimide in an extraction shell are introduced. In the course of the extraction, the contents of the flask become brownish-black. Upon working up the reaction mixture as in the preceding examples, *iso-indoline* having a boiling point of 92° at 10 mm. pressure is obtained; its picrate forms fine needles which melt at 192-193°.

EXAMPLE 7

N-ethyl-decahydro-isoquinoline

To 4.54 parts of lithium-aluminum-hydride in 300 parts by volume of absolute ether, 8.95 parts of *N*-acetyl-decahydro-isoquinoline dissolved in 300 parts by volume of absolute ether are added dropwise in such manner that the ether boils gently. Upon completion of the reaction, further proceeding is effected in accordance with the preceding examples, and there is thus obtained *N-ethyl-decahydro-isoquinoline* which boils at 92-94° at 12 mm. pressure. It forms a hydrochloride which melts at 203-204°.

EXAMPLE 8

2,3-bis-(N-ethyl-N-benzyl-aminomethyl)-pyridine

A solution of 30 parts of quinoline acid-bis-benzyl-ethylamide and 300 parts by volume of absolute ether is allowed to flow into 14.2 parts of lithium-aluminum-hydride in 300 parts of absolute ether. The contents of the flask immediately undergo a yellow coloration and boil gently. The addition is extended over a period of 2 hours. The reaction mixture is then heated for 22 additional hours on the water bath. After working up in accordance with the preceding example, *2,3-bis-(N-ethyl-N-benzyl-aminomethyl)-pyridine* is obtained as a colorless oil which boils at 78-80° under a pressure of 12 mm. Its hydrochloride melts at 179-180°.

EXAMPLE 9

1,2,3,4-tetrahydro-isoquinoline

14.7 parts of isodehydrocarbostyryl, dissolved in 300 parts by volume of absolute ether, are added dropwise within a period of two hours to the solution of 4.75 parts of lithium-aluminum-hydride in 300 parts by volume of absolute ether. Heating is then continued for 24 more hours at a bath temperature of 70°. The process is then carried out in accordance with the preceding examples and the desired base, *1,2,3,4-tetrahydro-isoquinoline*, is distilled at 106-108° under a pressure of 12 mm. The hydrochloride has a melting point of 192-193°.

EXAMPLE 10

9-aminomethyl-phenanthrene

10.5 parts of 9-phenanthryl-carboxylic acid-amide are introduced into an extraction shell. A solution of 3.5 parts of lithium-aluminum-hydride in 500 parts by volume

of absolute ether, in the apparatus, is heated until the shell is empty. After working up in accordance with the preceding example, there is obtained the 9-aminomethyl-phenanthrene which melts at 170°.

EXAMPLE 11

β-dimethylaminoethyl-benzhydryl ether

27 parts of diphenylmethoxy-acetic acid-dimethylamide, in 100 parts by volume of absolute ether, are added dropwise to the solution of 4.2 parts of lithium-aluminum-hydride in 400 parts of absolute ether. After working up in accordance with previous examples, *β-dimethylaminoethyl-benzhydryl ether* is obtained as an oil which boils at 122-125° at 0.1 mm. pressure. The hydrochloride melts at 159-160°; the picrate at 125-128°.

EXAMPLE 12

α-Phenoxy-ethylamine

20 6.9 parts of phenoxyacetamide are added dropwise to a solution of 4.6 parts of lithium-aluminum-hydride in 600 parts by volume of absolute ether, at such a rate that the solution boils gently. Upon completion of the reaction, the reaction mixture is decomposed with water, and the reaction mass, after acidification with sulfuric acid, is then extracted with ether. Thereupon it is made alkaline and again extracted with ether. This ether extract yields the *β-phenoxy-ethylamine* having a boiling point at 12 mm. pressure of 104°. Its picrate melts at 167-168°.

What we claim is:

30 1. A process for the preparation of an amine, which comprises reducing a carboxylic acid amide containing at least once the

35 grouping, such grouping being the sole reducible part of said amide, to an amine which has the same number of carbon atoms, by reacting it with lithium-aluminum-hydride in an anhydrous organic solvent which is inert under the reaction conditions, as the reaction medium, and at an elevated temperature decomposing the resulting reaction mixture with an aqueous medium, and isolating the amine which is formed.

40 2. A process for the preparation of an amine, which comprises reducing a carboxylic acid amide containing at least once the

45 45 grouping, such grouping being part of a ring and constituting the sole reducible part of said amide, to an amine which has the same number of carbon atoms, by reacting it with lithium-aluminum-hydride in an anhydrous organic solvent which is inert under the reaction conditions, as the reaction medium and at an elevated temperature, and isolating the amine which is formed.

50 3. A process for the preparation of an amine, which comprises reducing a carboxylic acid amide containing at least once the

55 55 grouping, such grouping being part of a straight chain and constituting the sole reducible part of said amide, to an amine which has the same number of carbon atoms, by reacting it with lithium-aluminum-hydride in an anhydrous organic solvent which is inert under the reaction conditions, as the reaction medium and at an elevated temperature decomposing the resulting reaction mixture with an aqueous medium, and isolating the amine which is formed.

60 4. A process according to claim 2, wherein the starting compound to be reduced is a lactam.

5. A process according to claim 2, wherein the starting compound to be reduced is a dicarboxylic acid imide.

6. A pyridine containing, as sole substituents, an N-lower-alkyl-N-aralkyl-substituted aminoethyl group in each of the 2- and 3-positions.

7. 2,3 - bis - (N - ethyl - N - benzyl - aminomethyl) - pyridine.

8. A process for the preparation of a pyridine which contains, as sole substituents, an N-lower-alkyl-N-aralkyl-substituted aminomethyl group in each of the 2- and 3-positions, which comprises reducing the corresponding quinolinic acid-bis-aralkyl-alkylamide to the amine by reacting the amide with lithium-aluminum-hydride in an anhydrous organic solvent which is inert under the reaction conditions, as the reaction medium, and at an elevated temperature, and isolating the resultant amine.

9. A process for the preparation of 2,3-bis-(N-ethyl-N-benzyl-aminomethyl)-pyridine, which comprises reducing quinolinic acid-bis-benzyl-ethylamide to the said pyridine by reacting the amide with lithium-aluminum-hydride in an anhydrous organic solvent which is inert under the reaction conditions, as the reaction medium, and at an elevated temperature, and isolating the resultant aforesaid pyridine.

10. A process for the preparation of β -dimethylaminoethyl-benzhydryl ether which comprises reducing diphenylmethoxyacetic acid-dimethyl-amide to the said

β -dimethylaminoethyl-benzhydryl ether by reacting the diphenylmethoxy-acetic acid-dimethyl-amide with lithium-aluminum-hydride in an anhydrous organic solvent which is inert under the reaction conditions, as the reaction medium, and at an elevated temperature, and isolating the resultant β -dimethylaminoethyl-benzhydryl ether.
